UNITED STATES PATENT OFFICE.

JOSEPH RENÉ AYOTTE, OF CHICAGO, ILLINOIS. ASSIGNOR OF ONE-HALF TO JULES X. RIVARD, OF CHICAGO, ILLINOIS.

SPARK-PLUG.

1,363,212.

Specification of Letters Patent. Patented Dec. 28, 1920.

Application filed July 19, 1919. Serial No. 311,961.

To all whom it may concern:

Be it known that I, JOSEPH RENÉ AYOTTE, a subject of the King of Great Britain, residing at Chicago, in the county of Cook and State of Illinois, have invented certain new and useful Improvements in Spark-Plugs, of which the following is a specification.

My invention relates to spark plugs.

One of the objects of the invention is to provide, preferably, a dual spark-gap plug in which separation between the electrodes, constituting the spark gap, will remain unchanged under varying changes of temperature of the plug; which is so constructed that very little heat is conducted from the central conductor to the unsupported end of the porcelain core, thereby avoiding spontaneous fracture or crizzling of the vitreous coating of the porcelain core, due to differences of temperature between the exterior and the interior surface of the core, when exposed to sudden drafts of air or drenching by water, or the like.

Still another object is to provide means whereby the length of the interior, or intensifying spark-gap will invariably be and remain of uniform length without being affected by the act of assembling the parts.

Other, further and more particular objects of the invention will become readily apparent, to persons skilled in the art, from a consideration of the following description when taken in conjunction with the drawings, wherein—

Figure 1 is a central axial section.

Fig. 2 is an inverted plan view.

Figs. 3, 4 and 5 are views of modified parts.

In all the views the same reference characters are employed to indicate similar parts.

Referring to the structure shown in Figs. 1 and 2, 6 is the usual threaded shell for containing the core 7. It is threaded, as at 8, and contains the lower electrode 9, which is secured to the lower annular, salient end of the shell, as usual in devices of this kind. One of the peculiar features of this portion of the device, however, is the bend, as at 10, between the vertical part 9 and the horizontal part 11, to give greater strength to the electrode.

A central conductor 12 passes through an enlarged axial opening 13 and is cemented therein by cement 14. Concentric with the opening 13 is a larger opening or cavity 15,

extending from near the end 16 of the core to a transverse plane near the top of the shell. The central conductor 12 is bent into a sinuous or double curve, as at 17, having parts 18 and 19 that extend laterally from the main portion 12 of the central conductor. Cemented in the opening 15 is the clamping structure 20 having a sleeve-like part 21 to be cemented in the opening 15 by cement 22, and having a coaxially arranged threaded stem 23 projecting thereabove, for a clamping nut 24. The sinuous end 17 of the conductor 12 has its parts 18 and 19 in closer proximity to the interior of the sleeve 21 so that the spark will always spring between one or both of these parts and the interior of the sleeve. Increased heat tending to cause expansion and elongation of the conductor 12, does not change the relation between the parts 18 and 19 and the interior of the sleeve, as the distance between these parts remains constant irrespective of the length of the conductor 12, within the limit of the device. The upper end of the conductor, which is further removed from the interior of the sleeve 21, is not a terminal of a spark gap, as usual in structures of this character. The air content of the sleeve 21 provides ample heat insulation between the conductor 12 and the surrounding porcelain core 7, thereby preserving the upper portion of the core relatively cool. When the sleeve 21 is placed in the opening 15 the upper end of the conductor 12 may be entirely disregarded and the parts 18 and 19 of the central conductor will be in close proximity to the sleeve so that the spark will take place between either of these parts and the interior of the sleeve, and the length of this gap can be depended upon to be of uniform extent, as the vertical movement of the sleeve 21 has no effect to increase or decrease the distance between the electrodes bounding the spark gaps. When it is desired to do away with the intensifying spark gap, and use other parts of the structure, the sinuous part 17 may be bent, as clearly shown in Fig. 4, whereby the parts 18 and 19, or either part, may be brought into actual contact with the interior of the sleeve so that there will be no spark within the interior of the sleeve, as in the first illustration. The springiness or resiliency of the central conductor 12 will be sufficient to maintain the parts in contact and any tendency to elonga-

tion of the central conductor will have the effect of increasing the actual metallic contact between the parts 18 and 19 and the interior of the sleeve, as any material relative 5 movement will keep the contacting parts bright and in good conducting condition.

In Fig. 4 I have shown an annular groove 25 in the part 20 to present a larger air radiating surface to disperse such heat, 10 above atmosphere, as may be imparted to this part of the structure. In Fig. 4 I have shown the outside of the sleeve 21 to be threaded, so that cement will more readily stick to it so that it will be held more readily 15 in the cavity 15, when cement is applied. In Fig. 5 I have shown the same sleeve to be knurled, as at 26, for the same purpose, whereas in Fig. 3 separated grooves 27 are placed in the sleeve within which cement 20 may be placed in the act of cementing the sleeve in the cavity in the upper end of the core. Either one, or any other similar variation from that shown will come within the contemplation of my invention. In Fig. 25 3 I have shown a different kind of a groove 25 for the purpose of radiating any heat that may be imparted to the sleeve, above atmospheric temperature.

While I have shown the upper end of the 30 central conductor 12 to be bent in a sinuous curve, it may be contorted in any other suitable manner in order to bring selected parts of the conductor within the striking distance of the interior of the sleeve within which it 35 is contained, and while I have shown several modifications of this portion of the spark plug structure having the outer surface of the sleeve roughened or otherwise made uneven to increase the tenacious effect 40 of the cement therewith, it will be manifest that other forms may and will be suggested to persons skilled in the art, for accomplishing this purpose.

While I have herein shown a single embodiment of my invention with several modifications, for the purpose of clear disclosure, it will be manifest that other forms and variations in configuration and disposition of the parts is within the scope of the 50 appended claims.

Having described my invention, what I claim is:—

1. A spark plug having in combinative association an insulating core, a sleeve of conducting material within the core, and forming one electrode of a spark gap and a conductor projecting into said sleeve in near proximity to the interior surface thereof between which and said conductor to produce the abrupt discharge that forms the spark. 55 60

2. A spark plug having in combinative association, a sleeve of conducting material directly connected to one terminal of the plug forming one electrode of a spark gap and a central conductor projecting into said sleeve 65 having a plurality of surface parts in near proximity to the interior surface of the side wall of the sleeve between one of which parts and the sleeve to produce the abrupt discharge which forms the spark. 70

3. A spark plug having in combinative association, a core, axially perforated for a central conductor, the upper end of the perforation terminating in an enlarged concentric cavity; a sleeve within the cavity, carrying a wire clamping part whereby to constitute one electrode of a spark gap and a central conductor having its upper end within the sleeve, forming the other electrode of said spark gap and forming an electrode for 80 another spark gap at the lower end of the plug. 75

4. A spark plug having in combinative association a core provided in its upper end with an enlarged cavity and an axially extending perforation communicating therewith; a sleeve cemented in said cavity, having on its upper end a screw threaded stem, said sleeve constituting one electrode of a spark gap; a central conductor in said core, 85 having its upper end bent to bring a part thereof, intermediate its ends, nearer the sleeve, constituting the other electrode of the spark gap and two electrodes at the lower end of the plug of which the central 90 conductor constitutes one of the latter electrodes. 95

In testimony whereof I hereunto subscribe my name.

JOSEPH RENÉ AYOTTE.
